United States Patent Office

Des. 211,209
Patented May 28, 1968

211,209

TRANSMISSION

Hans Hauser, Fredericktown, Ohio, assignor to The J. B. Foote Foundry Co., Fredericktown, Ohio, a corporation of Ohio

Filed May 17, 1967, Ser. No. 7,163

Term of patent 14 years

(Cl. D55—1)

FIG. 6 -

FIG. 7 -

FIG. 1 is a perspective view of a transmission embodying my new design, with the shift member and the power shaft shown in dotted lines;

FIG. 2 is a top plan view thereof;

FIG. 3 is a bottom plan view thereof;

FIG. 4 is a front elevation thereof;

FIG. 5 is a right side elevation thereof;

FIG. 6 is a rear elevation thereof; and

FIG. 7 is a left side elevation.

The dominant features of my design reside in those portions shown in full lines.

I claim:

The ornamental design for a transmission, substantially as shown and described.
